UNITED STATES PATENT OFFICE.

HENRY E. HALLBORG, OF NORFOLK, VIRGINIA.

SELF-COOLED IMPACT SPARK-GAP.

1,330,182.

Specification of Letters Patent. Patented Feb. 10, 1920.

Application filed July 20, 1916. Serial No. 110,290.

To all whom it may concern:

Be it known that I, HENRY E. HALLBORG, a citizen of the United States, and a resident of Norfolk, in the county of Norfolk and 5 State of Virginia, have invented a certain new and useful Improvement in Self-Cooled Impact Spark-Gaps; and it consists in the combinations, constructions, and arrangements herein described and claimed.

10 An object of my invention is to provide a quenched spark gap, which is highly efficient, light in weight, and relatively cheap to manufacture.

A further object of my invention is to 15 provide a device of the type described, which is especially reliable in its workings due to the absence of fan or blower protective devices, auxiliary leads, switches, etc., and to the further fact that it is self-contained and has nothing inflammable in its 20 construction.

A further object of my invention is to provide a device which is simple and may be easily operated.

25 Further objects and advantages will appear in the following specification, and the novel features of the invention will be particularly pointed out in the appended claims.

My invention is illustrated in the accompanying drawings forming a part of this 30 application; and in which:

Figure 1 is a side view of the device, certain parts being shown in section;

Fig. 2 is a perspective view of one of the 35 radiating units;

Fig. 3 is a face view showing an insulating gasket as applied to a unit;

Fig. 4 is a perspective view of another of the radiating units;

40 Fig. 5 is an enlarged section of a portion of the device shown in Fig. 1; and

Fig. 6 is an end view of the device.

In carrying out my invention, I provide a suitable base 1 to which is secured end supports 2. Extending between the end supports is a pair of micarta rods 3, while at 45 the top of the uprights 2 is a frame 4. Referring now particularly to Fig. 5, it will be seen that the device is made up of a series

50 of units, these units consisting of a circular disk 5, preferably copper, having a comparatively deep recess 6 on one face and a relatively shallow recess 7 on the opposite face. The face having the recess 7 is

55 further recessed to provide room for a chemically pure silver disk 8, whose edges

are slightly machined away, as shown at 8*. This silver disk 8 is soldered to the body portion 5 with a semi-hard solder made by increasing the lead content of ordinary solder to raise the melting point of the same. The object of this procedure is to avoid heating the silver during manufacture, to a temperature at which it will absorb impurities, as would be the case with silver 60 solder or hard solder. A further reason is to insure a melting temperature of the solder well above that resulting due to the heating by the spark in actual operation. Half of the units have segmental rims 9. 70 The units are assembled in pairs back to back, one without the rim and one with the rim, as shown in the drawing. When assembled the openings formed by the registering recesses 6 allow free air circulation 75 between each pair of sparking surfaces, and make the internal walls of the air chamber thus formed effective in radiating the heat due to the spark.

Each unit has two radiating vanes 10. 80 Obviously any number of these may be provided as long as the total radiating surface provided is enough not to dissipate more than 5 watts per square inch. The object of keeping the outside diameter of the units 85 small is to more nearly equalize the temperature between the bottoms and tops of the radiating vanes 10, since metal radiates heat faster at the higher temperature. This is the reason for the length of the gap and 90 the comparatively small diameter of the units. The annular space 7 between the units is made shallow in order to inclose a minimum amount of air in the sparking chamber. This construction permits of the 95 use of a mica gasket 11, or other mechanically strong, but only semi-airtight gasket, without impairing the tone due to the air leakage. The air in the chamber is consumed more rapidly than it can leak in sufficient quantities to impair the tone. The gaskets 11 are retained in position and alinement by the pins 12 spaced 120° apart. This permits of rapid assembling and disassembling 100 of the units without disturbing the individual gasket alinement. 105

The micarta rods 3 support the plates and furnish temporary alinement. The plates when assembled are clamped by means of a clamping screw 14 between the 11 heads 15. This affords a construction which holds the plates securely, and yet which per-

mits the device to be readily taken apart for inspection or repair.

The operation of the gap differs from the usual type of gap, in that the quenching of the spark is more rapid, resulting in lower current in the gap circuit and lower energy losses in this circuit. The coupling between the antenna and gap circuits can therefore be made closer, with a corresponding increase in energy input to the antenna. The spark gap spacing is so chosen that the resistance of the gap is at its maximum, or near this maximum. This maximum value of spark resistance has been found to vary with the diameters of the sparking surfaces and has a critical value for each. The spacing is so selected that increase or decrease of sparking distance causes a drop in gap resistance, other conditions being the same.

I claim:

1. A self cooled spark gap comprising a series of units, each of said units having relatively large registering recesses arranged to form an air chamber between contiguous units, said air chamber having communication with the outer atmosphere, and relatively small recesses adapted to form annular air chambers between contiguous units, opposed sparking surfaces carried by the contiguous units, and non-air tight gaskets disposed between the sparking surfaces and arranged to pass through said annular air space, whereby the air space between the sparking surfaces is rendered semi-air tight.

2. A self cooled spark gap comprising a series of units, each of said units having relatively large registering recesses arranged to form an air chamber between contiguous units, said air chamber having communication with the outer atmosphere, relatively small recesses adapted to form annular air chambers between contiguous units, opposed sparking surfaces carried by the contiguous units, non-air tight gaskets disposed between the sparking surfaces and arranged

to pass through said annular air space, whereby the air space between the sparking surfaces is rendered semi-air tight, the space between the sparking surfaces being such that the resistance of the gap is substantially at its maximum.

3. A self cooled spark gap comprising a series of units, said units being placed back to back in pairs, the backs of each of said units having relatively large registering recesses arranged to form an air chamber between the units, means for affording communication between the air chamber and the outer atmosphere, each unit having a centrally disposed sparking surface and having an annular recess contiguous to and concentric with said sparking surface, and a relatively thin non-air tight gasket for spacing the sparking surfaces of contiguous units apart, said gasket being arranged to extend beyond the abutting edges of the contiguous units, and means for holding and centering said gasket.

4. A self cooled spark gap comprising a series of units, said units being placed back to back in pairs, the backs of each of said units having relatively large registering recesses arranged to form an air chamber between the units, means for affording communication between the air chamber and the outer atmosphere, each unit having a centrally disposed sparking surface and having an annular recess contiguous to and concentric with said sparking surface, a relatively thin non-air tight gasket for spacing the sparking surfaces of contiguous units apart, said gasket being arranged to extend beyond the abutting edges of the contiguous units, means for holding and centering said gasket, said last named means comprising a series of pins carried by said units and arranged at 120° apart.

HENRY E. HALLBORG.
